UNITED STATES PATENT OFFICE.

CHARLES E. WHITE AND GEORGE ELLIOTT, OF WASHINGTON, DISTRICT OF COLUMBIA.

ARTICLE-HOLDING DEVICE.

1,072,680.

Specification of Letters Patent.

Patented Sept. 9, 1913.

Application filed June 23, 1913. Serial No. 775,210.

To all whom it may concern:

Be it known that we, CHARLES E. WHITE and GEORGE ELLIOTT, citizens of the United States of America, and residents of the city of Washington, in the District of Columbia, have invented certain new and useful Improvements in Article-Holding Devices, of which the following is a specification.

This invention relates to certain new and useful improvements in devices for holding newspapers, napkins, towels and other articles and while in the present instance it is shown as designed more particularly as a newspaper cabinet or device for holding newspapers, it will be understood that the same principle can be readily applied to the holding of napkins as in a restaurant, towels as in a barber shop or other articles which are placed in piles and used one after the other.

The present invention has for its objects among others to provide a simple and cheap, yet durable, reliable and efficient device of this character whereby the papers or other articles will be held against accidental displacement or being blown away by the wind and yet the top paper or other article easily removed without disturbing the others. The basic principle involved is that of a roller holder designed to rest upon the uppermost paper, to be revolved as the uppermost paper is removed and to automatically gravitate so as to rest upon the next lowermost paper or other article in connection with which it may be used.

The character of the cabinet or stand may vary as to shape, size, number of compartments and general appearance, the principle involved being applicable to various forms of stands or cabinets and while designed as portable, it will be evident that the same may be permanently fixed to a wall or other support.

Other objects and advantages of the invention will hereinafter appear and the novel features thereof will be particularly pointed out in the appended claims.

The invention, in its preferred form, is clearly illustrated in the accompanying drawings, which, with the numerals of reference marked thereon, form a part of this specification, and in which—

Figure 1 is a perspective view of one form of embodiment of the invention. Fig. 2 is a cross section on the line 2—2 of Fig. 3 looking in the direction of the arrows, Fig.

3 is a cross section on the line 3—3 of Fig. 1 looking down. Fig. 4 is a horizontal section, looking down, of a slightly modified form.

60

Like numerals of reference indicate like parts throughout the different views.

Referring to the drawings, 1 designates a cabinet or stand, in the present instance shown as divided into a multiplicity of compartments for the purpose of holding newspapers or the like, the compartments permitting of the assortment of the papers so that they may be kept separate, that is, all the papers of one kind kept by themselves. 65 A cabinet with a single compartment, however, where desired may be provided.

2 is a gravitating roller holder for the papers or other articles. It is designed to rest upon the uppermost paper of the stack, 70 as indicated clearly in Fig. 2, and to automatically drop as paper after paper is removed, as will be understood by the dotted lines in Fig. 2. Where a plurality of compartments is provided, as in Figs. 1 and 2, 75 a plurality of rollers 2 will be provided, one for each compartment. The rollers have their ends confined in vertical grooves 3 in the uprights 4, as shown, so that they may be free to gravitate and also to rotate as the 80 papers are withdrawn.

In order to insert the papers, the roller is moved up, the papers placed beneath the same as indicated and the roller then allowed to drop until it rests upon the uppermost paper or other article. When a customer desires a paper, he simply takes hold of the outer edge of the uppermost paper and pulls it out. The more quickly it is pulled, the more easily it comes, but in any 85 case it can be readily removed without disturbing the next lowermost paper.

In Fig. 4 we have shown the roller 5 as provided with enlargements 6 upon its ends, the outer ends of which enlargements preferably have rounded edges, as indicated, and these ends work in grooves in the uprights 7, as shown, the strips in which said grooves are formed being provided with flanges or analogous means 8 which, while permitting 100 the roller to gravitate and to revolve, permit its displacement; in this form the roller is applied or placed in position before the top portion of the cabinet is secured in place. The operation is the same as in the form previously described.

While the form of roller and guides shown

in Fig. 4 is there illustrated in a stand having but one compartment, it is evident that the form of stand shown in Fig. 1 may have all of its rollers of this character. Also that while it is desirable in the form of stand shown in Fig. 1 to have the rollers have each compartment separate and independent of each other, owing to the likelihood of varying heights of papers in different compartments, a single roller may be employed for plurality of compartments.

Modifications in details may be resorted to without departing from the spirit of the invention or sacrificing any of its advantages.

What is claimed as new is:—

1. A device for holding papers and like articles, consisting of a supporting stand having a rest for the articles, uprights hav-

ing grooves and a gravitating roller mounted for rotation and vertical movement in 20 said grooves and means for holding said roller against displacement therefrom.

2. A device for holding papers and the like, comprising a supporting stand having a rest for the articles, uprights having 25 grooves, and a gravitating roller having its ends revoluble in said grooves and adapted to rest upon the uppermost paper and to be revolved by removal of such paper.

Signed by us at Washington, D. C., this 20
21st day of June, 1913.

CHARLES E. WHITE,
GEORGE ELLIOTT.
